Primary Examiner—Louis S. ZarfasAssistant Examiner—Monica A. WeingartAttorney, Agent, or Firm—Cislo & ThomasCLAIM

The ornamental design for resistant exercise pants, as shown and described.

DESCRIPTION

FIG. 1 is a front perspective view of my resistant exercise pants showing my new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top view thereof; and,
FIG. 7 is a bottom view thereof.

The broken line showing of a person in FIG. 1 is for illustrative purposes only and forms no part of the claimed design.
